UNITED STATES PATENT OFFICE.

IRA W. EDDY, OF PROVIDENCE, RHODE ISLAND, ASSIGNOR, BY DIRECT AND MESNE ASSIGNMENTS, TO GARDNER C. LUTHER, OF SWANSEA, MASSACHUSETTS.

COMBINED SAND-BAND AND SCRAPER FOR VEHICLE-WHEELS.

SPECIFICATION forming part of Letters Patent No. 760,685, dated May 24, 1904.

Application filed September 30, 1903. Serial No. 175,144. (No model.)

To all whom it may concern:

Be it known that I, IRA W. EDDY, a citizen of the United States of America, and a resident of Providence, in the county of Providence and State of Rhode Island, have invented certain new and useful Improvements in a Combined Sand-Band and Scraper for Vehicle-Wheels, of which the following is a specification.

This invention relates to novel improvements in a combined sand-band and scraper or clearer for vehicle-wheels; and it consists, essentially, of a wheel-hub having a projecting ring or annular guard member secured to its inner or rear end arranged to form outer and inner peripheral grooves, in combination with a sand-band adapted to be mounted on a wheel-axle provided with an annular flange adapted in use to inclose said guard member and having an opening therethrough in its under side and a scraper located contiguous to said opening and in yielding engagement with the ring, all as will be more fully hereinafter set forth and claimed.

I am well aware that vehicle-wheels have been provided with sand-bands and scraping devices long prior to my present invention, and therefore I disclaim such former construction.

The invention herewith possesses a greater degree of efficiency and utility, it is more cheaply constructed, it is more easily and quickly applied to the axle and hub, and is readily adjusted and secured in position on the axle.

By means of my invention it becomes practically impossible for sand to enter the axle-box of the hub. At the same time, too, the device prevents any oil that may escape from the box or bearing to flow onto the outer surface of the hub. These advantages are secured independently of the condition of the leather washers used—that is to say, even though the wheel be very loosely "washed" or worn the device is equally as efficient as though the wheel were newly washed. I may add incidentally that the scraper or clearer is as efficient when the wheel is re-

volved backward as when it is revolving in the normal direction or forward.

In the accompanying drawings, Figure 1 is a longitudinal central sectional view showing my invention in its normal position and relation to a wheel-hub and axle. Fig. 2 is a front end view of the sand-band and scraper. Fig. 3 is a corresponding rear or outer view of the same, and Fig. 4 is a perspective view of the scraper itself.

A, again referring to the drawings, designates a wheel or vehicle hub of usual construction provided with a metal axle box or bearing *a* and axle *b*, the latter being turned and fitted to the bore of said axle-box and having interposed washer members *w*, all as usual. The face of the rear or inner end of said hub is provided with a projecting annular ring or metal guard member *c*, its form cross-sectionally being triangular, thereby producing a V-shaped outer groove *d* and an independent inner V-shaped groove *d'*. The outer face of the guard is substantially parallel with the hub's face. The guard may be secured to the hub in any suitable way. As drawn, it has a series of integral spur-like projections *a'*, which are forced or driven into the hub. The location of the guard is about midway between the axle-box and the outer band *a'*, all as clearly shown.

The sand-band proper, *h*, is adapted to be mounted on the square or shank part *b'* of the axle and is provided with an overhanging annular flange *h'*, the face of the latter when in use being located contiguous to the face of the hub *A* and inclosing within the chamber thus formed the guard *c*. The said member *h* is separable and consists of two parts, which are secured together by means of screws *s*. The lower side of the flange *h'* is cut away at *m* to permit the sand, oil, &c., to pass freely from the sand-band's chamber.

The device is further provided with a scraper or clearer member *e*, made, preferably, of thin sheet metal, as steel, the same having a substantially U-shaped form and adapted to be mounted in the bottom of the square opening

formed in the sand-band *h* for the reception of the shank of the axle. The inner side or blade portion *e*' of the scraper is or may be bent laterally to make it more resilient, the 5 same extending downwardly and bearing flat-wise against the face of the guard-ring *c*. After the device has been placed in proper position longitudinally of the axle it may be rigidly secured in place by means of a set-screw *s*', tapped into the under side of the hub 10 of the sand-band, the screw at the same time bearing against the base of the interposed scraper *e*, thereby maintaining the latter in position also, all as shown in Fig. 1.

15 Assuming now that the several members comprising my invention to have been constructed, arranged, and mounted substantially as represented in Fig. 1, the operation may be described as follows: Any sand, dirt, &c., 20 that may work in the space between the face of the revolving hub and the non-revolving flange *h*' will be caught in the outer groove *d* and deflected therefrom by gravity into the opening *m* of the sand-band. In case any 25 oil or foreign matter works out from the axle box the same will be caught in the inner or lower groove *d*' of the guard-ring. When the oil overflows the last-named groove and onto the face of the ring or guard, the latter 30 in revolving carries such overflow around until arrested by the stationary resilient blade portion *e*', which latter operates to scrape or clear the oil from the guard onto the blade, and from the latter it falls to the earth. It 35 will be seen that the blade is somewhat pointed and extends below the guard-ring.

In case the scraper becomes worn out or inoperative it is a comparatively simple matter to remove it and substitute a new one, the 40 cost being merely nominal. The other members of the device are practically as durable as the vehicle itself.

I do not desire to limit the shape of the guard-ring, &c., to the exact form represented 45 in the drawings, as it is evident that minor changes may be made therein without departing from the spirit of the invention.

I claim as new and desire to secure by United States Letters Patent—

1. As an improved article of manufacture, 50 the combined sand-band and scraper or clearer hereinbefore described, the same consisting of a guard-ring adapted to be secured to the hub of a vehicle-wheel, a sand-band having an overhanging flange cut away or open on its 55 under side, and a scraper or clearer member adapted when in use to be in continuous engagement with the face of said guard-ring, said sand-band and clearer capable of being 60 adjustably secured to the axle.

2. The combination with a wheel-hub and a projecting concentric guard-ring secured thereto and forming outer and inner grooves, *d*, *d*', respectively, of an axle member having said hub mounted thereon, a sand-band mounted on said axle provided with an overhanging apertured flange forming a chamber inclosing said guard-ring, a clearer member in continuous yielding engagement with the face of the guard, and means for securing the sand-band 70 and clearer in position on the axle.

3. The combination with a wheel-hub and a guard-ring secured thereto, of an axle, a sand-band mounted thereon, a resilient scraper member engaging said guard-ring, said scraper 75 being bent and seated in the sand-band, and a set-screw mounted in the hub of said band and bearing against the base of the scraper, the latter being interposed between the axle and screw, whereby the members are adjustably secured in position upon the axle.

4. In a device of the class hereinbefore described, provided with a revoluble guard-ring and a non-revoluble sand-band, a sheet-metal scraper or clearer member mounted in said 85 sand-band having the blade portion thereof in yielding engagement with and extending beyond the outer diameter of said ring.

Signed at Providence, Rhode Island, this 21st day of September, 1903.

IRA W. EDDY.
